UNITED STATES PATENT OFFICE

2,682,667

METHOD OF MAKING WINDOWED ARTICLES
OF WEARING APPAREL

Donald L. Michelstetter, Milwaukee, Wis.

Application November 9, 1950, Serial No. 194,908

1 Claim. (Cl. 2-205)

2

1 My invention relates to improvements in weather protective wearing apparel.

More particularly stated my invention relates to improvements in a head dress whereby the sensitive portions of the face of the wearer may be protected and visibility may be unimpaired; whereby a head dress including a facial covering may be provided with a windowed opening to provide clear vision; whereby the window of a windowed opening for a weather protective facial covering may be attached to the facial covering in a satisfactory manner; whereby a window may be so mounted in a knitted stocking cap that the interior surface of the window is exposed when it is in a retracted position above the eyes of the wearer; whereby a window incorporated in the construction of an extension for a helmet head dress is marginally inserted in the extension.

My invention further relates to a method whereby a windowed facial protective sub-assembly may be attached to a head dress, and whereby the actual window material may be secured to the material of an article of wearing apparel.

In the drawings:

Fig. 1 illustrates my head dress as it appears upon the head of a person when the face protective windowed band is folded in retracted position.

Fig. 2 is a view similar to Fig. 1 but showing the windowed band in face protecting position over the face of the wearer.

Fig. 3 is a front elevation of my head dress with the face protective band foldably retracted, a portion of the side wall of my head dress being broken away to show the fold in vertical section.

Fig. 4 is a front elevation of my head dress with the face protective band in fully extended position.

Fig. 5 is a perspective of the window sub-assembly including the window material, and the tape mounting means secured thereto, a portion being broken away to show a section illustrating my flange construction.

Fig. 6 is a section on line 6-6 of Fig. 4.

Figs. 7, 8, 9 and 10 illustrate in vertical section successive steps in my new method of mounting a window member on a garment, each of the figures showing in section the sub-assembly of Fig. 5 juxtaposed with the head dress material to which the sub-assembly is attached.

Fig. 11 is a view similar to Fig. 3 but showing an alternative form of window and windowed opening in a head dress.

Fig. 12 is a view similar to Fig. 4 but showing the alternative window and window opening in accord with the Fig. 11 construction.

Like parts are designated by the same reference characters throughout the several views.

I shall describe below the incorporation of my invention in a stocking cap made of suitable wearing apparel material and particularly the typical rib knit cap. Such a cap 15 is generally tubular and the top end is drawn together and closed, as by sewing or stitching. The end is puckered and is concealed by a pompon 16.

10 As shown in Fig. 2, the tubular body portion of my cap 15 is of such length, when extended, that the rearward part of the lower margin 17 is drawn down snugly upon the neck of the wearer and the forward portion is disposed over the tip 15 of the nose of the wearer. When this lower margin is thus extended, the eyes of the wearer are covered and I provide a windowed opening at 18 to provide full vision for the wearer. It is to the provision of the windowed opening at this location, to the construction thereof, and the method 20 by which the window is installed that my invention is directed.

It will be particularly noted that when the lower portion or band of the tubular construction of my head dress is folded upward to a retracted position shown in Fig. 1, this folded portion 20 overlies the forehead or the upper part of the forehead of the wearer and the interior surface of the window 21 is exposed.

25 As shown in Fig. 3, it is common in the construction of stocking caps made of ribbed knit material to provide a double tubular body in which there is an inner tube 22 and an outer tube 23. To those who are skilled in this art, it will be recognized that the opening of a window space 18 in this knitted material presents ravelling problems. Since it is impractical to provide a knitted selvage for this window space, I solve this problem as described below.

30 Furthermore, the difficulties presented in the provision of a windowed opening for a head dress of this type, include the provision of a satisfactory transparent material to which it is possible to attach the material of the head dress 15 by sewing or other practical attaching means. I have found 45 that cellulose acetate in transparent sheet form is the preferred material for this purpose, and I have devised a new method and structure for mounting a plastic window through the use of tape flanges as will now be described.

40 The window 21 is preferably ovoid in shape. About its margins I attach a tape 25, the central portion of the tape being channeled at 26 about the edges of the window and a line of stitching 50 27 is sewed through the tape and through the

3

plastic to permanently attach the tape 25 to the window. Thus two flanges 28 and 29 of tape material extend outwardly at either side of the margins of the window.

The next steps in my process of attaching the window 21 to the head dress 15 are illustrated successively in Figures 7 to 10, where it will be seen that the sub-assembly shown in Fig. 5 is placed against the exterior of the tubular knit material 23. Flange 28 of tape material 25 is folded at 30 and at 31 in order that it may be sewed at 32 to the head dress 15 (see Fig. 8). When it has been sewed all around the window 21, it solidly binds the tubular knit material 22-23 to the tape 28 whereby to prevent ravelling of the knit material. I then excise the window opening by cutting the knit material along the dotted line shown at 33 in Fig. 8, thus leaving a ravel controlled but otherwise raw edge at 34 (see Fig. 9). The window and its tape then may assume the position shown in Fig. 9 in which the window 21 is substantially aligned with the plane of the material. I then fold flange 29 as shown in Figs. 9 and 10 so that a line of stitching 35 may be extended through the folded tape at 36 to finish the window inserting operations.

I thus provide the double lines of stitching, 32 and 35, to doubly bind and prevent ravelling of the margins 34 of the window opening, and because the raw edges of the tape flanges, 28 and 29, are folded in, before the stitching operation, the completely finished job is a smooth and attractive taped binding for the windowed opening.

In the alternative form of construction shown in Figs. 11 and 12, I shape a plastic window 40 as shown in the drawings, and I provide a tape binding and flanges only for the margins 41, 42 and 43. The edge of the window coinciding with the margin of the head dress at 44 is a raw plastic edge, untaped and unbound. This alternative construction is advantageous where the

4

provision of knitted material along the extended lower margin 17 of the head dress is objectionable. A curve at the edge of the plastic at 50 may be provided to conform to the nose or face of the wearer.

I claim:

The method of making a windowed article of wearing apparel including the making of the article of wearing apparel without a window opening, making a window sub-assembly including a centrally channeled tape-like member marginally flanged, and securing the tape about the margin of a window element with the window margin in the channel, applying the sub-assembly against the surface of the article of apparel to be windowed, securing one of the flanges to one side of the article of apparel along a line exterior of the window element, excising an area of the article of apparel within the said line and finally securing the other flange to the other surface of the article.
